WEANER

Ray M. Prose and Henry F. Prose, Medoc, Kans.

Application November 9, 1935, Serial No. 49,105

1 Claim. (Cl. 119—130)

This invention relates to weaners, one of the objects being to provide a calf and colt weaner of sturdy and efficient construction which can be made and sold at low cost.

5 A further object is to provide a weaner having a new and novel arrangement of spikes which serve to prevent the calf or colt from thrusting the device back by brushing it along the flank of the mother.

10 Another object is to provide a weaner which will not interfere with the free breathing of the calf or colt and will permit the animal to graze easily.

15 A still further object is to provide a weaner which can be applied and removed readily by the attendant and can be quickly fitted to heads of different sizes.

With the foregoing and other objects in view which will appear as the description proceeds, 20 the invention consists of certain novel details of construction and combinations of parts herein-after more fully described and pointed out in the claim, it being understood that changes may be made in the construction and arrangement 25 of parts without departing from the spirit of the invention as claimed.

In the accompanying drawing the preferred form of the invention has been shown.

In said drawing

30 Figure 1 is side elevation of the weaner.

Figure 2 is a section on line 2—2, Figure 1.

Figure 3 is a view showing in detail a portion of the weaner.

Figure 4 is an enlarged section on line 4—4, 35 Figure 2.

Referring to the figures by characters of reference, 1 designates an arcuate shield plate the top and bottom edges of which are bent back onto the front convex face of the plate to provide reinforcements 2 and 3 while tongues 4, integral with the ends of reinforcement 2, are looped and riveted to form eyes 5 for engagement by attaching links 6.

The lower reinforcement 3 has a series of 45 alined openings forming sockets 7 in which are seated and welded the butt ends of spikes 8 and 9. These spikes are alternately arranged, the spikes 8 being extended at right angles to the plate 1 while the spikes 9 are extended beyond the lower end of the plate along lines parallel with the plate and then merge into forwardly extended prongs 10 parallel with the spikes 8.

Side straps 11 formed of metal or other stiff material are formed with closed loops 12 at their lower ends through which the angular links

6 extend. Similar closed loops 13 at the upper ends of straps 11 are engaged by rings 14 supported in turn by an adjustable supporting strap 15 adapted to go over the top of the animal's head.

An upper strap 16 connects the rings 14 and is adapted to extend across the head under and close to the neck while another lower strap 17, which is adjustable, connects the two links 6 and is arranged to go across the back of the head adjacent to the mouth. These two straps 16 and 17 are connected by a stiff strip 18, preferably folded to provide three thicknesses and end loops 19 and 20. Strap 16 extends through loop 19 while loop 20 is slotted at 21 to receive a ring 22 having laterally extended lugs 23 seated in the loop. The lower strap 17 is extended through ring 22.

In practice the straps 16 and 17 are adjusted about the head of the calf or colt beneath its neck so that plate 1 will rest on the nose. Strap 15 will of course support the weaner in position where none of the parts will interfere with grazing.

The weaner can be worn by the calf or colt without discomfort but any attempt made by the animal to reach the udder of its mother will result in the spikes 8 first engaging the flank and when the calf or colt then pushes back on the weaner, the ends of spikes 8 will act as fulcrums for the L-shaped spikes 9—10 the points of which will thus be thrust into the udder. Because of the sensitiveness of the tender udder, the mother will promptly kick or flight away the calf or colt which will soon become discouraged and proceed to graze.

Importance is attached to the fact that the spikes do not go through the plate 1 but are welded in the sockets provided therefor. Thus the back surface is left smooth and will not cause discomfort. The L-shaped spikes provide open spaces between them through which the animal can breathe and no apertures are necessary in the plate 1 for that purpose. It will be noted that the free ends of all of the spikes are disposed in an imaginary surface parallel with the plate 1. Thus all of the spikes are equally effective.

Obviously any attempt made by the animal to thrust the weaner upwardly along the head and out of the way will be resisted by the stiff strips 16 and 18 at the sides and under the head.

What is claimed is:

A weaner including an arcuate plate having folded upper and lower edge portions constitut-

ing reinforcements, spikes secured in the lower reinforcement and abutting against the plate, said spikes being arranged in two series alternately disposed, the spikes of one series being extended outwardly from and at right angles to said reinforcement and the spikes of the other series being extended downwardly along and bearing backwardly against the reinforcement, the lower portions of said downwardly extend-

ed spikes being extended outwardly substantially parallel with the first named spikes and below the centers of the spaces between them, the free ends of all of the spikes being disposed in an imaginary surface parallel with the plate, and means for attaching the plate to the head of an animal.
